GRANVILLE B. STONE, OF BOSTON, MASSACHUSETTS.

MANIKIN BALL-PLAYER.

1,036,024.

Specification of Letters Patent. Patented Aug. 20, 1912.

Application filed February 9, 1912. Serial No. 676,603.

To all whom it may concern:

Be it known that I, GRANVILLE B. STONE, a citizen of the United States, residing at Boston, in the county of Suffolk and State 5 of Massachusetts, have invented certain new and useful Improvements in Manikin Ball-Players, of which the following is a specification, reference being had to the accompanying drawings.

10 This invention comprehends certain new and useful improvements in game apparatus and relates particularly to game apparatus of the aerial projectile type, the present device being intended to represent and simulate 15 the actions of a ball player, whereby the device may be used for such games as parlor base ball, or for other purposes which will be apparent to those skilled in the art to which this invention appertains.

20 The invention has for its primary object a simple, durable and efficient construction of manikin ball player, the parts of which may be cheaply manufactured and readily assembled and which may be actuated at 25 any required or reasonable distance.

The invention also has for its object an improved construction of manikin ball player provided with a removable cup or basket which may be easily applied to the 30 bat carried by the arms of the manikin, whereby a ball may be thrown by the device, and which may be easily removed, whenever desired, when for instance it is desired to have the manikin simulate the 35 actions of a batter, instead of a ball tosser or thrower. And the invention also aims to generally improve this class of devices and to render them more useful and commercially desirable.

40 With these and other objects in view, as will more fully appear as the description proceeds, the invention consists in certain constructions, arrangements and combinations of the parts that I shall hereinafter 45 fully describe and claim.

For a full understanding of the invention, reference is to be had to the following description and accompanying drawing in which,

50 Figure 1 is a side elevation of a manikin ball player constructed in accordance with the principles of my invention. Fig. 2 is a front elevation thereof. Fig. 3 is a detail perspective view of one of the arms of the manikin, and, Fig. 4 is a fragmentary perspective view of a bar employed.

Corresponding and like parts are referred to in the following description and designated in the accompanying drawing by like reference characters.

Referring to the drawing, the numeral 1 designates a base plate which may be of any desired size or design, according to the particular requirements of the case, or as judgment or taste may dictate, and which 60 is provided with openings 2 therein for the reception of screws 3 or similar fastening devices, whereby to secure the base plate to a pair of longitudinally extending and laterally spaced strips 4. A cross bar or brace 65 5 is secured upon the strips 4 at one end thereof by screws 4' or the like, whereby to securely brace the supporting stand of the device.

A manikin 6 of conventional base ball 75 player design is mounted on the plate 1 and is formed at about the shoulder portion thereof with a transverse opening 7 extending therethrough. A pivot bolt 8 is mounted in the opening 7 and is arranged to have 80 secured to its ends, the right and left arms designated 9 and 13, respectively. The arm 9 is formed in the rear of its pivot with a lug 10 and is provided at its opposite end with an enlargement 11 designed to be secured 85 in a substantially rectangular socket 12^a formed in a bar 12 intermediate of the ends of the latter. This bar 12 is formed at one extremity with a hook 15, to which one 90 end of a contractile spring 14 is secured, the other end of said spring being secured to the side of the manikin 6 by a screw 14^a or similar fastening device.

The left end arm 13 is preferably of sheet metal, whereby it may be easily bent to the 95 required shape, one end of said arm being curled around and thus secured to the bar 12 between the enlarged socket portion 12^a of said bar and the shouldered extremity 12^b from which the hook 15 projects. By 100 this means, the arm 13 is securely attached to the bar 12. The opposite end of the arm 13 is apertured, whereby to fit upon the pivot bolt 8 which, as has been hereinbefore set forth, is mounted in the transverse opening 105 7 of the manikin.

In order to limit the forward movement of the bar 12 to a predetermined point, by the forwardly and downwardly swinging movements of the arms 9 and 13 and by the 110 action of the contractile spring 14, I provide a stop 17 designed to engage the arm 9 when

the parts 9, 13 and 12 are in the position illustrated in Fig. 1.

A catch 16 is pivotally secured to the rear of the figure or manikin 6, said catch being 5 designed to engage the lug 10 of the arm 9, so as to hold the arms and the bar 12 in their relative rearward position with the spring 14 under tension, and in order to release the catch 16 from the lug 10 so as to 10 permit the spring 14 to act, a cable, cord, or the like, as designated at 18, is secured at one end to the catch 16, is passed through an eye 18^a secured to the base 1 and is extended to any desired length and connected 15 to a handle 19 of any desired form of construction.

It is, of course, desirable to limit the rearward or upward movement of the parts so as to avoid excessive strain or tension being 20 imposed upon the spring 14, and it will be noted that this action is successfully performed by the angular disposition of the relatively free end of the arm 13, as best indicated at 13^b in Fig. 2.

25 From as much of the description as has preceded in connection with the accompanying drawing, it will be understood that the manikin may be easily set for operation by swinging the arms 9 and 13 upwardly so as 30 to permit the catch 16 to engage the lug 10 of the arm 9. The spring 14 will thus be placed under tension. It is then only necessary to pull upon the cord 18, whereupon the catch 16 will be released from the lug 35 10 of the arm 9 and the spring 14 will be permitted to act to swing the arms 9 and 13 forwardly and downwardly and carry the bar 12 forwardly. This bar 12 is designed to perform two functions. It is not only 40 intended for use as a bat to simulate the ordinary base ball bat in the hands of a player, but is also intended for use in throwing the ball. To arrange the bar 12 for this last named purpose, I provide it with a cup 45 or basket 20 which is adapted to be slipped over and be frictionally held upon the free end of the bar or bat so that a pellet or the like received in the basket or cup will be ejected therefrom and the act of throwing 50 the ball simulated when the manikin operates. When the ball is to be batted by the manikin and not thrown, the cup or basket 20 is removed from the bar or bat 12.

In using the device to bat the ball, the 55 manikin is removed from its supporting stand and placed on its side, and the pellet or the like which serves as the ball, is struck by the finger so as to cause it to slide over the surface upon which the manikin is laid. 60 One hand of the player is used for thus causing the ball to slide over the said surface toward the uplifted bat or bar 12, it being understood that the spring will be arranged in said position during this operation, and 65 the other hand of the operator grasps the

handle 19, so that as the ball or pellet comes close to the point where the relatively uplifted bat is located, the cable or cord 18 is pulled and the device actuated to strike the ball.

70 It is to be understood that the spring 14 may be in the form of a rubber band as well as a metallic coiled spring and that various other changes may be made in the construction, arrangement and proportions of the 75 parts without departing from the scope of the invention, as defined in the appended claims.

75 It will be seen that I have provided a very simple and efficient game device, the 80 operation of which will imitate, to a considerable degree, the attitude of a ball player and his motions, even in batting the ball which is thrown to him or throwing the ball to some player, and that, therefore, the 85 device will be found useful and interesting in playing the game of table base ball, or for other general amusement purposes.

85 What I claim is:—

90 1. A device of the character described, including a supporting stand, a manikin supported thereon, said manikin being provided with pivoted arms, a bar connected to said arms, a contractile spring operatively connected to said bar and to a stationary portion of the device, one of said arms being 95 formed in the rear of its pivot with a lug, a catch adapted to engage said lug, and means operable at a distance for disengaging the catch from the lug.

100 2. A device of the character described, including a stand, a manikin supported thereon and provided with pivoted arms, a bar formed intermediate of its ends with a socket, one of said arms being provided with an extremity adapted to fit in said socket and the other arm being curled around the bar below the socket, the bar being formed at its lower extremity with a hook, a contractile spring secured to said hook and to a stationary portion of the device, one of the arms being formed with a lug, a catch adapted to engage said lug, and means operable at a distance for releasing the catch from the lug.

110 3. A device of the character described, including a manikin provided with pivoted arms, a support for the manikin, a bar connected to said arms, one of the arms extending across the front of the manikin for the 115 purpose specified, a contractile spring connected to said bar and to a stationary portion of the device, one of the arms being formed in the rear of the pivot with a lug, a catch mounted on the rear of the manikin 120 and adapted to engage said lug, and means operable at a distance for disengaging the catch from the lug.

125 4. A game device of the character described, including a manikin, a support 130

therefor, the manikin being provided with pivoted arms, a stop secured to the side of the manikin and adapted to engage one of said arms to limit its movement in one direction, a bar connected to the free ends of said arms, a contractile spring connected to said bar and to a stationary portion of the device, one of said arms being provided in the rear of its pivot with a lug, a catch adapted to engage said lug, and means operable at a distance for disengaging the catch from the lug. 20

means operable at a distance for disengaging the catch from the lug.

6. A device of the character described, including a manikin provided with pivoted arms, a bar connected to said arms, a detachable cup mounted upon said bar, a 25 spring arranged to swing said arms in one direction, one of said arms being formed in the rear of its pivot with a lug, a catch adapted to engage said lug to hold the arms with the spring under tension, and means 30 operable at a distance for disengaging the catch from the lug.

5. A game device of the character described, including a manikin provided with pivoted arms, a bar connected to said arms, a contractile spring arranged to swing said arms in one direction, one of said arms being formed in the rear of its pivot with a lug, a catch adapted to engage said lug, and

In testimony whereof I hereunto affix my signature in the presence of two witnesses.
